UNITED STATES PATENT OFFICE.

WILLIAM F. BROWN, OF NEWARK, NEW JERSEY, ASSIGNOR TO THE BIGELOW CARPET COMPANY, OF MASSACHUSETTS.

DESIGN FOR CARPET.

SPECIFICATION forming part of Design No. 27,619, dated August 31, 1897.

Application filed July 14, 1897. Serial No. 644,575. Term of patent 3½ years.

To all whom it may concern:

Be it known that I, WILLIAM F. BROWN, a subject of the Queen of Great Britain, and a resident of Newark, in the county of Essex and State of New Jersey, have invented a new and original Design for a Carpet and Border, of which the following is a specification.

This invention comprises two parts—namely, the design A for a carpet and the design B for a border; and I do hereby declare that the drawing accompanying this specification conveys to any one a clear understanding of the same and is sufficient to enable such person to use my invention.

15 The design A is characterized by large and small separated circular figures.

The design B is characterized by urn-like figures connected by festoons of flower and leaf forms, with large ornamental figures be-

tween the urn-like figures and curving stem-work below the urn-like figures.

What I claim, and desire to secure by Letters Patent, is—

1. In a design for a carpet, the body A, substantially as shown. 25

2. In a design for a carpet, the border B, substantially as shown.

3. The design for a carpet comprising the body A and the border B, substantially as shown. 30

In testimony whereof I have signed my name to this specification in the presence of two subscribing witnesses.

WILLIAM F. BROWN.
